(57) **CLAIM**

The ornamental design for a writing instrument as shown and described.

DESCRIPTION

FIG. 1 is a top front perspective view of a writing instrument;

FIG. 2 is a bottom front perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan view thereof; and,

FIG. 9 is a section view of the writing instrument taken through line “9-9” shown in FIG. 3.

The broken lines in the drawings illustrate portions of the writing instrument, which form no part of the claimed design.

1 Claim, 7 Drawing Sheets
